VAPOR GENERATOR

Gilbert C. Whitney, Jr., New York, N. Y., assignor
to Foster Wheeler Corporation, New York, N. Y.,
a corporation of New York

Application December 7, 1939, Serial No. 307,957

17 Claims. (Cl. 122—479)

This invention relates to vapor generators, and more particularly pertains to the method of, and apparatus for, recovering heat in vapor generators. The invention will be disclosed in connection with steam generators, but it will be understood that it is applicable to vapor generators generally.

The major problem encountered in the operation of economizers in steam generators wherein some steam is formed in the economizer, has been the separation of the steam and water from the mixture thereof which is ordinarily present at the economizer outlet, before the mixture enters the steam and water drum of the boiler. The need for this separation, aside from steam washing, is primarily due to the practical limitations that are imposed on the diameter and wall thickness of the drums. The drums should be of sufficiently ample dimensions to provide adequately for the separation of the mixture of steam and water normally liberated therein by the boiler tubes, but the size of the drums becomes excessive if they are required to separate an additional mixture of steam and water received from a steaming economizer. Under these conditions, the use of a steam washer of adequate proportions in the drums would be practically impossible even though a mixture of steam and water could be effectively used to wash steam.

However, there are numerous instances particularly in connection with modern high pressure steam generators, where various factors entering into the design and operation of such units make the joint use of both steaming economizers and steam washers highly desirable. The washers are necessary on account of the relatively high concentration of solids occurring in the boiler circulating water, and because of superheated steam requirements with respect to turbine operation, while steaming economizers are essential because of the high temperatures (1200°—1400° F.) of the flue gases, and because of the relatively large amount of this heat that can be recovered most economically from these gases by a steaming economizer.

For example, in any such high pressure installation, the maximum heat recovery possible by air heating surface is limited by the maximum air temperatures permissible with the existing fuel burning equipment, while stage bleeding of turbines has reduced the heat recovery possible in non-steaming economizers by increasing feed water temperatures to levels regularly above 400° F. and at times as high as 500° F. at the

5 economizer inlet. Ordinarily therefore, since furnace gas temperatures are substantially fixed by final steam temperature requirements, there would be a margin of several hundred degrees that would have to be absorbed by additional boiler heating surface ahead of the economizer in point of gas flow, or by a steaming economizer. However, in most cases the installation of additional boiler surface is very difficult due to drum limitations, and in all instances exceedingly expensive, based on the amount of heat recovery thus attainable, whereas additional economizer heating surface is much cheaper and more effective for the purpose specified.

10 15 The present invention provides means whereby steaming economizers may be advantageously used to recover heat which would normally be wasted in steam generators and the like. The invention also provides means for controlling final steam temperatures by the temperature of the steam leaving the steaming economizer.

20 25 30 35 40 45 In accordance with the method and apparatus of the invention, the major portion of the total feed water is withdrawn from an intermediate header in the economizer, which is located at a point in the economizer where the water has almost, but not quite, reached saturation temperature at the pressure existing in the boiler drum. The solid water thus withdrawn from the economizer is led directly to the steam washer in the steam and water drum of the boiler. The water which is permitted to continue through the remainder of the economizer is of such an amount that by the time it reaches the outlet header it is vaporized and is in the form of saturated or slightly superheated steam. This steam may be led either to a point in the drum below the steam washer or directly to the inlet of the superheater. The intermediate header is so located in the economizer that regardless of operating conditions only solid water will be delivered to the steam washer. The economizer is thus divided into a steaming section, and a non-steaming section, with the steaming section containing sufficient heat absorbing surface so that the economizer as a whole will effect the desired reduction in the temperature of the flue gases.

50 55 The invention will be understood from the following description when considered in connection with the accompanying drawings forming a part thereof, and in which:

Fig. 1 is a partial vertical sectional view, illustrating more or less diagrammatically, a steam generator embodying one form of the invention;

Fig. 2 is an enlarged transverse vertical sec-

tional view of part of the boiler steam and water drum, and

Fig. 3 is a view similar to Fig. 1 but illustrating another form of the invention.

Like characters of reference refer to the same or to similar parts throughout the several views.

Referring to Figs. 1 and 2 of the drawings, reference character 10 designates generally the setting of a steam generator comprising an upper or steam and water drum 11, and a main bank of steam generating tubes 12, which are vertically inclined and extend between headers 14 and 15 and a drum 13. Drum 13 is connected with the upper drum 11 by means of a group of riser tubes 16, and headers 14 and 15 are connected to drum 11 by downcomers 17. Water wall tubes 18, 19 and 20 also form a part of the steam generating surface and the circulatory system of the unit. The combustion chamber 21 is lined by these water wall tubes, and suitable fuel burning equipment, not shown, produces the necessary products of combustion in the furnace.

Suspended from the upper portion of the setting and extending downwardly into the space between the tubes 16 and 17, is a superheater 22 having steam inlet and outlet headers 23 and 24 respectively. The inlet header 23 is connected to the steam and water drum by saturated steam line 25. Combustion gases leave the steam generating surface of the boiler through outlet flue 26 and flow through duct 27 to an economizer 28 which comprises a steaming section 29, and a non-steaming section 30. As shown, the gases after leaving the economizer, enter an air heater 31, which includes suitable air ducts, not shown, for conducting preheated air to the fuel burning apparatus in the lower portion of the combustion chamber 21, while the spent flue gases are discharged to the atmosphere by a stack or any other means, also not shown.

As shown more clearly in Fig. 2, the steam drum 11 is provided with steam washing means 32 and steam drying means 33. Any suitable type of steam washer may be employed, since the washing means forms no part of the invention. The washing means shown includes a tray 34 horizontally disposed above the water line in the drum, and provided with a plurality of parallel, elongated upwardly extending nozzle-like ports 35. Extending over the top of each of these ports, and slightly spaced therefrom is a cap member 36, the lower edges of the sides of which are serrated as indicated at 37. Feed water from the economizer is supplied to the tray 34 by a feed line 38. A body of this water flows across the tray between the ports to an outlet pipe 39 the upper end of which is disposed so as to maintain the desired water level on the tray. Pipe 39 also conducts the overflow from the tray to the boiler circulating water in the lower portion of the drum. Steam liberated in the space below the washer passes upwardly through the ports or nozzles 35 in the tray, is deflected by the cap members 36, and flows downwardly through the water on the tray and under the lower edges of the sides of the cap members, and then upwardly through the water to the space in the drum above the washer. The steam, which by its contact with the fresh feed water has been substantially freed of its solid content, flows through the drier 33 to the steam line 25 and thence to the superheater.

Feed water is supplied to the economizer from any suitable source by a feed pump 40, which is controlled by the usual feed water regulator 41, whereby the desired water level is maintained in

the boiler drum at the various boiler ratings. This controlled amount of feed enters the economizer inlet header 43 through line 42, and flows through the non-steaming section 30 to an intermediate header 44. The inlet end of the boiler feed line 38 is connected to the header 44, and as shown in Fig. 1, a fixed orifice 45 is placed in this line at a point between the economizer and the boiler drum. The diameter of the orifice is such that the major portion of the total feed in the form of solid water flows from the header 44 through line 38 directly to the steam washer, while the smaller amount of the feed which continues through the steaming section 29 of the economizer will, at the outlet thereof, be in the form of saturated or slightly superheated steam. This steam is led from outlet header 46 through line 47 to the lower portion of the boiler drum.

In the form of the invention illustrated in Fig. 3, the steam from the steaming section of the economizer instead of flowing to the drum, is conducted by line 47 directly to the inlet header 23' of the superheater where, together with the saturated steam from the boiler, it flows through the superheater to the outlet header 24'. A thermostat bulb 48 is disposed in the header 24' and it is connected by a pressure line 49 with a motor valve 50 in the feed line 38. By means of the thermostat bulb, the motor valve is automatically regulated by the final temperature of the superheated steam in the header 24', and thus controls the flow through the feed line, and the amount of water flowing through the steaming section of the economizer, to the end that the temperature of the steam flowing through line 47 may be controlled so as to effect the final temperature of the superheated steam. It will be understood that at all times, an ample supply of solid water will be delivered to the steam washer, and that normally only a very slight variation in flow through the steaming section of the economizer will be sufficient to produce the required change in temperature of the steam generated therein to serve as a means for superheat control. Obviously, if the already limited amount of water flowing through the steaming section is reduced, the temperature of the steam therein will be readily increased by the heat of the flue gases.

In operation therefore, when the final temperature of the superheated steam falls below a certain predetermined level, the thermostat bulb 48 will actuate the motor valve 50 through the pressure line 49 so as to withdraw more water from the intermediate header 44 through line 38, which results in rapidly increasing the temperature of the steam in the steaming section. The heating effect of this hotter steam when introduced into the superheater header will increase the final temperature of the superheated steam until it returns to the desired level. The operation is reversed when the superheated steam temperature becomes too high.

It will be apparent, that in accordance with the invention, steaming economizers may be advantageously and economically employed from the standpoint of both heat recovery and steam washing in modern high pressure steam plants. The invention not only provides for the admission of feed water containing no steam to the steam washer, but also provides a ready means for controlling superheat.

Although by way of example I have disclosed preferred embodiments of the invention, it will be understood that changes may be made in the particular form and arrangement of the various

parts of the apparatus herein disclosed without departing from the principles of the invention, and that the invention is not to be limited excepting by the scope of the appended claims.

What is claimed is:

1. In a vapor generator, a vapor generating section, a vapor and liquid drum connected to the vapor generating section, a vapor and liquid contacting device in the drum, a gas passage arranged to receive gases after flowing in heat exchange relationship with the vapor generating section, a heat exchange device in said gas passage having a portion in which liquid is heated and a connecting portion in which heated liquid is vaporized, means for delivering liquid to the first mentioned portion of the heat exchange device, a conduit for delivering heated liquid from said liquid heating portion of the heat exchange device to the vapor and liquid contacting device in the drum, and a separate conduit for conducting vapor from the vaporizing portion of the heat exchange device to a point of use.

2. In a vapor generator, a vapor generating section, a vapor and liquid drum connected to the vapor generating section, a vapor superheater for the generator, a gas passage arranged to receive gases after flowing in heat exchange relationship with the vapor generating section, a heat exchange device in said gas passage having a liquid heating portion and a liquid vaporizing portion, means for delivering liquid to the heat exchange device, a conduit for delivering heated liquid from said liquid heating portion to the drum, and a separate conduit connected to the outlet of the vaporizing portion and to the inlet of the superheater.

3. In a vapor generator, a vapor generating section, a vapor and liquid drum connected to the vapor generating section, a vapor and liquid contacting device in the drum, a gas passage arranged to receive gases after flowing in heat exchange relationship with the vapor generating section, a heat exchange device in said gas passage having a portion in which liquid is heated and a connecting portion in which heated liquid is vaporized, means for delivering liquid to the first mentioned portion of the heat exchange device, a conduit for delivering heated liquid from said liquid heating portion of the heat exchange device to the vapor and liquid contacting device in the drum, a flow controlling device in said conduit, and a separate conduit for conducting vapor from the vaporizing portion of the heat exchange device to a point of use.

4. In a vapor generator, a vapor generating section, a vapor and liquid drum connected to the vapor generating section, a vapor and liquid contacting device in the drum, a gas passage arranged to receive gases after flowing in heat exchange relationship with the vapor generating section, a heat exchange device in said gas passage having a portion in which liquid is heated and a connecting portion in which heated liquid is vaporized, means for delivering liquid to the first mentioned portion of the heat exchange device, a conduit for delivering heated liquid from said liquid heating portion of the heat exchange device to the vapor and liquid contacting device in the drum, a flow controlling device having a fixed orifice in the conduit, the flow area of the orifice being such that all the liquid delivered to the heat exchange device is withdrawn therefrom through said conduit excepting for that part which will be vaporized in the vaporizing por-

tion, and a separate conduit for conducting vapor from the vaporizing portion to a point of use.

5. In a vapor generator, a vapor generating section, a vapor and liquid drum connected to the vapor generating section, a vapor superheater for the generator, a gas passage arranged to receive gases after flowing in heat exchange relationship with the vapor generating section, a heat exchange device in said gas passage having a liquid heating portion and a liquid vaporizing portion, means for delivering liquid to the heat exchange device, a conduit for delivering heated liquid from said liquid heating portion to the drum, a valve in the conduit, thermostatic means responsive to the temperature of the vapor leaving the superheater for controlling the valve to decrease the flow of fluid to the vaporizing portion when the temperature of the superheated vapor falls below a predetermined level and increase said flow when the temperature of the superheated vapor rises above a predetermined level, and a separate conduit for delivering vapor from the vaporizing portion to the superheater.

6. In a steam generator, a steam generating section, a steam and water drum connected to said section, a steam washer in the drum, a gas passage arranged to receive gases after flowing in heat exchange relationship with said section, an economizer in said passage having a portion in which water is heated and a connecting portion in which steam is generated, means for delivering feed water to the first mentioned portion of the economizer, a conduit for delivering heated water from the water heating portion of the economizer to the steam washer in the drum, and a separate conduit for conducting steam from the steam generating portion of the economizer to another part of the generator.

7. In a steam generator, a steam generating section, a steam and water drum connected to said section, a steam washer in the drum, a gas passage arranged to receive gases after flowing in heat exchange relationship with said section, an economizer in said passage having a portion in which water is heated and a connecting portion in which steam is generated, means for delivering feed water to the first mentioned portion of the economizer, a conduit for delivering heated water from the water heating portion of the economizer to the steam washer in the drum, and a separate conduit for delivering steam from the steam generating portion to the steam and water drum.

8. In a steam generator, a steam generating section, a steam and water drum connected to said section, a steam washer in the drum, a gas passage arranged to receive gases after flowing in heat exchange relationship with said section, an economizer in said passage having a portion in which water is heated and a connecting portion in which steam is generated, means for delivering feed water to the first mentioned portion of the economizer, a conduit for delivering heated water from the water heating portion of the economizer to the steam washer in the drum, a flow controlling device having a fixed orifice in said conduit, the flow area of the orifice being such that all the feed water delivered to the first mentioned portion of the economizer is withdrawn therefrom through said conduit excepting for a predetermined part which will be vaporized in the steam generating portion, and a separate conduit for withdrawing steam from the steam generating portion.

9. In a steam generator, a steam generating

section, a steam and water drum connected to said section, a steam superheater for the generator, a steam washer in the drum, a gas passage arranged to receive gases after flowing in heat exchange relationship with said section, an economizer in said passage having a water heating portion and a steaming portion, means for delivering feed water to the economizer, a conduit for delivering heated water from the water heating portion to the steam washer in the drum, a valve in the conduit, thermostatic means responsive to the temperature of the steam leaving the superheater for controlling the valve to decrease the flow of water to the steaming portion when the temperature of the superheated steam falls below a predetermined level and increase said flow when the temperature of the superheated steam rises above a predetermined level, and a separate conduit for delivering steam from the steaming portion to the superheater.

10. The method of generating steam in a steam generator having a steam generating section, a steam and water drum and a steam washer in the drum, which comprises flowing feed water through a heating zone and into a steam generating zone both zones being in heat exchange relationship with gases produced in firing the generator, separately conducting steam free water from said heating zone to the steam washer in the drum, vaporizing the portion of the heated feed water passing into said steam generating zone, and conducting the vaporized portion to a zone of use.

11. The method of generating steam in a steam generator having a steam generating section, a steam and water drum and a steam washer in the drum, which comprises flowing the feed water through a heating zone and into a steam generating zone both zones being in heat exchange relationship with gases produced in firing the generator, separately conducting steam free water from said heating zone to the steam washer in the drum, vaporizing the portion of the heated feed water passing into the steam generating zone, and delivering the vaporized portion to the drum.

12. The method of generating steam in a steam generator having a steam generating section, a steam and water drum and a steam washer in the drum, which comprises flowing the feed water through a heating zone and into a steam generating zone both zones being in heat exchange relationship with gases produced in firing the generator, separately conducting steam free water from said heating zone to the steam washer in the drum, controlling the flow of steam free water to the washer, vaporizing the portion of the heated feed water passing into the steam generating zone, and conducting the vaporized portion to a zone of use.

13. The method of generating steam in a steam generator having a steam generating section, a steam and water drum and a steam washer in the drum, which comprises flowing the feed water through a heating zone and into a steam generating zone both zones being in heat exchange relationship with gases produced in firing the generator, separately conducting steam free water from said heating zone to the steam washer in the drum, regulating the flow of steam free water to the washer so that all the feed water introduced into said heating zone will be delivered to the washer excepting for a prede-

termined part thereof which will vaporize in said steam generating zone, withdrawing from the steam generating zone the vaporized portion of the feed water, and conducting the vaporized portion to a zone of use.

14. The method of generating steam in a steam generator having a steam generating section, a steam and water drum, and a steam washer in the drum, which comprises flowing the feed water through a heating zone in heat exchange relationship with gases produced in firing the generator, conducting heated water from said zone to the steam washer in the drum, vaporizing a portion of the feed water in a steaming zone disposed in heat exchange relationship with said gases, delivering said vaporized portion of the feed water to a superheater, and regulating the flow of heated water to the washer in response to the temperature of the steam leaving the superheater in such manner that the flow is increased when said temperature falls below a predetermined level and the flow is decreased when said temperature rises above a predetermined level.

15. The method of generating and superheating steam in a steam generator having a steam generating section and a steam and water drum, which comprises flowing the feed water through a heating zone in heat exchange relationship with gases produced in firing the generator, conducting heated water from said zone to the drum, vaporizing a portion of the feed water in a steaming zone disposed in heat exchange relationship with said gases, delivering said vaporized portion of the feed water to a superheater, and controlling the temperature of the steam leaving the superheater by regulating the quantity of feed water vaporized in said heating zone in response to the temperature of the steam leaving the superheater.

16. In a vapor generator, a vapor generating section, a vapor and liquid drum connected to the vapor generating section, a vapor superheater for the generator, a vapor and liquid contacting device in the drum, a gas passage arranged to receive gases after flowing in heat exchange relationship with the vapor generating section, a heat exchange device in said gas passage having a liquid heating portion and a liquid vaporizing portion, means for delivering liquid to the heat exchange device, a conduit for delivering heated liquid from said liquid heating portion to the vapor and liquid contacting device in the drum, and a separate conduit connected to the outlet of the vaporizing portion and to the inlet of the superheater.

17. The method of generating and superheating steam in a steam generator having a steam generating section, a steam and water drum and a steam washer in the drum, which comprises flowing feed water through a heating zone in heat exchange relationship with gases produced in firing the generator, conducting heated water from an initial portion of said zone to the steam washer in the drum, vaporizing heated water in a final portion of said zone, delivering said vaporized portion of the feed water to a superheater, and controlling the temperature of the steam leaving the superheater by regulating the quantity of feed water vaporized in said heating zone in response to the temperature of the steam leaving the superheater.

GILBERT C. WHITNEY, JR.
